DOORCHECK

Gustav A. Carlson, Chicago, Ill., assignor to The
Boye Needle Company, Chicago, Ill., a corpora-
tion of Illinois

Application March 19, 1934, Serial No. 716,364

4 Claims. (Cl. 16—84)

This invention relates to a door check or cushioning device for doors and the like. This invention constitutes an improvement upon my Patent 1,931,172, granted October 17, 1933, and upon 5 my co-pending application, Serial No. 672,873, for Door check.

An object of the invention is to provide improved means for cushioning the closing of a 10 door or the like and means for automatically resetting the cushioning apparatus every time that the door is opened. The invention is particularly useful in connection with screen doors which are urged toward the door frame by springs. 15 Other specific objects and advantages will appear as the specification proceeds. The invention is illustrated, in a preferred embodiment, by the accompanying drawing, in which—

Figure 1 is a plan view of my improved device showing the device applied to a door and door 20 frame, the latter parts being shown in section; Fig. 2, a sectional view of the cushioning device, the section being taken as indicated at line 2 of Fig. 1; Fig. 3, a sectional view, the section being taken as indicated at line 3 of Fig. 1; and Fig. 4, 25 a transverse sectional view, the section being taken as indicated at line 4 of Fig. 1.

In the illustration given, A designates a door 30 frame provided with a door jamb A'; and B designates a door hinged to the frame. The door is drawn toward the door frame by tension spring 19.

In the use of the specific embodiment illustrated, 35 a bracket or keeper member 11 is secured directly to the jamb A'. The bracket is provided with spaced arms 12 between which is secured a vertical pin 13. About the pin is rotatably carried a roller (not shown).

Secured to the door B is a tubular casing member 14 equipped at its rear side with an integral 40 supporting flange 15. The flange is provided with a web attachment portion 16 provided at its ends with perforations 17 through which screws may be passed to secure the flange to the door. Adjacent the forward open end of tube 14 are formed integral locking pins 18 diametrically disposed 45 on the tube 14. A cap 19 is provided with cylindrical sides 20 having bayonet slots 21 therein adapted to receive pins 18. The head is also provided with a guide-boss 22 having a square opening 50 therethrough adapted to receive the square stem 23. The head 19 is also provided with oil openings 24 on opposite sides of the boss 22. Integrally formed with the head 19 is a supporting flange 25 having integrally formed therewith an

attachment web 26. The web is provided at its ends with attachment openings 27.

The stem 23 is provided at its outer end with a head or catch member 28, the head 28 being provided with a gooseneck bend 29 which centers the head with respect to the stem 23 and also with respect to the pin 13. The head 28 is provided with a lateral slot 30 of substantially uniform width, and adjacent the forward end of the slot is a forwardly extending lip 31.

The stem 23 is provided with a reduced inner 5 end portion 32. A flexible head 33 is received on the reduced end 32 and secured thereon between spaced washers 34 by means of a screw 35, which 10 threadedly engages a tapped opening in the end 15 of the stem. A disk 36 is held between the screw head 35 and the outermost washer 34. The flexible plunger head 33 is provided with a cylindrical wall 37 adapted to engage the inner walls of the tube and to form a tight seat therewith. 20

In the operation of the cushioning device, there 25 is a tendency for the cylindrical wall 37 of the plunger head 33 to curl inwardly and thus break the seal. In order to straighten the cylindrical wall 37 and to maintain it in the proper parallel relation with the tube walls, I provide the rear 30 end 38 of the tube with an annular guide-flange 39, as shown more clearly in Fig. 2. It will be noted that there is a space provided between the cam walls of the flange 39 and the walls of the tube into which the cylindrical wall 37 of the 35 plunger head is guided, thus straightening the cylindrical wall to its desired shape.

The rear wall of the tube is preferably recessed 40 centrally and a tiny orifice 41 formed therein through which air may be slowly released in the cushioning operation of the device.

In order that the plunger may be retracted to its full limit and to increase the ease of operation thereof, I enlarge the bore of the tube near its 45 forward end, as indicated by the numeral 40. The enlargement tends to break the vacuum slightly and to permit the plunger to be withdrawn to its full limit. This insures accurate operation.

In the operation of the device, with the door 50 in closed position, as shown in Fig. 1, when the door is opened, the pin 13 or its roller engages the outer jaw of the head and causes the valve stem 23 to be retracted. The outward swinging of the door finally causes the pin to clear the slot of 55 the head and leaves the stem 23 in fully withdrawn position. When the door is closed, the lip extension 31 is brought into contact with the pin 13 and guides it into the slot 30. The uniform width of the slot prevents rattling and insures a 55

quiet sure movement in the closing of the door. The contact between the head and the pin forces the piston head 33 inwardly toward the rear wall of the tube. The slow escape of air through the 5 orifice 41 results in a cushioning of the stem and it allows the door to come against the door jamb slowly and silently. The square stem is retained by the square opening in boss 22 against rotary movement so that the head 23 is always held in 10 proper alignment with the pin 13.

The foregoing detailed description has been given for clearness of understanding only, and no unnecessary limitations should be understood therefrom, but the appended claims should be 15 construed as broadly as permissible, in view of the prior art.

I claim:

1. In combination with a door and door frame, supports carried by said door and door frame, a 20 stem reciprocally guided in one of said supports, means associated with said last mentioned support for cushioning the rearward movement of said stem, said means comprising a closed tube having its rear wall provided with an air-release 25 orifice and with an air-tight head secured to the inner end of said stem, said tube having an enlarged bore near its forward end, and releasable interlocking members carried by the other support and by the free end of said stem, one of said interlocking members comprising a stud and the other 30 interlocking member comprising a head having a laterally extending slot, said slot having an open end adapted to receive said stud.

2. In combination with a door and door frame, 35 supports carried by said door and door frame, a

stem reciprocally guided in one of said supports, means associated with said last mentioned support for cushioning the rearward movement of said stem, said means comprising a closed tube having its rear wall provided with a minute air-release orifice and with a substantially air-tight head secured to the inner end of said stem, said tube having an enlarged bore extending to one extremity of the tube and releasable interlocking members carried by the other support and by the 10 free end of said stem.

3. A door check comprising: a pair of supports, one adapted to be secured to a door and the other to a door frame, a closed tube secured to one of said supports, said tube having a minute orifice at 15 one end, a stem reciprocally guided in said tube, a piston head secured to the inner end of said stem, said tube being provided with an enlarged bore at one extremity thereof wherein said piston may move freely at the end of its stroke, and interlocking connections carried by the other support and by the free end of said stem.

4. A door check comprising: a pair of supports, one adapted to be secured to a door and the other to a door frame, a closed tube secured to one of said supports, said tube having a minute orifice at one end, a stem reciprocally guided in said tube, and a piston head secured to the inner end of said stem, said tube having a bore of substantially 25 uniform diameter except that, at least at one end portion thereof, the bore is enlarged so that the piston may move freely therein at the end of its 30 stroke.

GUSTAV A. CARLSON.
